Patented Jan. 18, 1966

203,524

TANDEM WING VTOL AIRCRAFT

Peter F. Girard, La Mesa, Calif., assignor to The Ryan
Aeronautical Co., San Diego, Calif.

Filed Apr. 19, 1965, Ser. No. 84,842

Term of patent 14 years

(Cl. D71—1)

Des. 203,524

PAGE 2

Fig. 3

Fig. 4

Fig. 5

Fig. 7

Fig. 6

FIGURE 1 is a perspective view of a tandem wing VTOL aircraft, showing my new design, the aircraft being in the cruising flight configuration;

FIGURE 2 is a perspective view from the opposite side thereof with the aircraft in vertical flight configuration;

FIGURE 3 is a side elevational view thereof;

FIGURE 4 is a top plan view thereof;

FIGURE 5 is a bottom plan view thereof;

FIGURE 6 is a rear elevational view thereof; and

FIGURE 7 is a front elevational view thereof.

I claim:

The ornamental design for a tandem wing VTOL aircraft, as shown and described.
